UNITED STATES PATENT OFFICE.

PERLEY L. KIMBALL, OF BELLows FALLS, VERMONT, ASSIGNOR TO VERMONT FARM MACHINE COMPANY, OF BELLows FALLS, VERMONT, A CORPORATION OF VERMONT.

CENTRIFUGAL CREAM-SEPARATOR.

No. 859,185.

Specification of Letters Patent.

Patented July 2, 1907.

Application filed January 26, 1906. Serial No. 298,049.

To all whom it may concern:

Be it known that I, PERLEY L. KIMBALL, a citizen of the United States of America, residing at Bellows Falls, in the county of Windham and State of Vermont, 5 have invented certain Improvements in Centrifugal Cream-Separators, of which the following is a specification.

This invention relates to improvements in centrifugal cream-separators such as that described and shown 10 in U. S. Letters Patent No. 806,346, dated December 5, 1905, and it consists in an improved construction of the liquid subdividers within the bowl, and in the simplification of the construction of the parts through 15 which the separated cream and skimmilk are withdrawn from the bowl and discharged from the apparatus. These improvements are specifically set forth in the following description and illustrated in the accompanying drawings, wherein—

Figure 1 is a central vertical section of the apparatus 20 with all its parts in normal operative position; Fig. 2 is a plan of the under side of the cover as seen when removed from the bowl; Fig. 3 is a plan of the top of a disk which is interposed between the cover and the liquid subdividers in the bowl; Fig. 4 is a plan of a 25 single subdivider, removed from the bowl; Fig. 5 is an elevation of two subdividers in their normal interlocked position; Fig. 6 is a diametrical vertical section of a single subdivider such as shown in Fig. 4; Figs. 7, 8, 9 and 10 are details showing modifications 30 in the construction of the means by which the several blades of the subdividers are held together and permanently spaced.

Referring to the drawings, the bowl A upon the spindle B, the feed-tube a having a base-plate b perforated 35 at b² secured near its lower end and axially radial wings g attached to its exterior, the passages for the whole milk in the tube beneath the plate b a boss b' projecting up from the bottom of the bowl, over which the lower end of the feed-tube fits, and also a slot in the 40 lower end of this tube which engages a pin p in the bottom of the bowl to prevent independent turning of the tube and plate therein, are all the same as shown in said Patent No. 806,346 and are not claimed herein.

The novel features are in the construction of the cover 45 C, with a chambered neck c' provided at its lower end with an annular diaphragm c² which, as shown, is substantially continuous with the base of the cover and has a central opening for the feed-tube a which closely fits it. Below the cover-base and between it and the 50 liquid subdividers in the bowl, is an annular disk D, the central opening in which also closely fits the feed-tube a. The diameter of the disk is substantially the same as that of the interior of the bowl and an annular groove c³ is formed in the downwardly projecting

flange of the cover opposite to the peripheral edge of 55 the disk D, when in normal position, for the passage of the skimmilk upward around the edge of the disk and then inward along the spaces between the disk and the cover-base. From the under side of the diaphragm c², a continuous rib c⁴ projects; as illustrated the outline of this rib is annular and is located a little within the peripheral circle of the lower end of the chamber c' of the neck. This continuous rib, however, may be of any polygonal form in circumferential outline if desired, and serve the same purpose. 60

In the upper surface of the disk D is a strip of packing material d' of the same outline as and coincident with the rib c⁴, so that when the cover and disk are in normal operative position, the rib c⁴ will bear upon the packing strip d' and form a cream chamber e between the diaphragm c² and disk, around the feed-tube a, closed from the skimmilk passages. Within the area of the chamber e an adjustable cream outlet is provided through the disk D. This outlet consists of a screw-plug f with a hole f' located eccentrically therein. Through the 70 diaphragm c², also within the area of the chamber e, a cream passage is formed and this is connected by a closed tube t with the cream discharge opening g' in the side of the neck below its upper edge, which in this construction is the location of the final discharge of the 80 skimmilk. If desired, the rib c⁴ may be formed upon the upper side of the disk D and the packing strip d' inserted in the under side of the diaphragm c², and the two will then serve the purpose of forming a cream chamber equally well. Through the diaphragm c², but 85 outside the periphery of the rib c⁴, a series of holes h are provided for the passage of the skimmilk from the space between the cover-base and the disk D into the chamber c' of the neck, from which chamber the skimmilk is finally discharged over the upper edge of the 90 neck. In this improved construction the division-plates, which have sometimes been called the "liner" of the bowl and which facilitate the separation of the cream from the blue-milk within the bowl, consist of a number of interlocking liquid subdividers, 95 individually made up of a series of parallel blades i longitudinally in the form of involute curves, similar to those shown in said Patent No. 806,346; but in place of a flat annular plate to which such blades are secured upon each side, the several blades are made wider, and 100 each plate is attached to the one adjacent thereto upon each side, by rigid connecting devices k which are secured to two adjacent blades, at intervals along their length and throughout the series of blades. Various forms of such connecting devices are available for the 105 purpose, details of some of which are illustrated in Figs. 7 to 10; but the preferable form for simplicity and economy of construction is that shown in Fig. 7 and also em-

bodied in the structures illustrated in Figs. 1, 4, 5, 6; for, by placing two of these thin metal pieces *k* together, inserting their respective narrow projecting ends through coincident holes in adjacent blades *i* and turning the ends of the respective pieces in opposite directions up against the sides of the blades, they will be firmly held together and permanently spaced at the location of each pair of connecting pieces; and as these are placed at proper intervals throughout the series of 10 blades, each subdivider will become a firm, durable structure, and when the blades of each are interlocked with those of another, the connecting pieces *k* will serve as fixed abutments for the free lateral edges of the blades, the same as though there was a continuous plate. 15 The interiorly threaded thimbles or spacing rings with a screw-pin to pass through the blades shown in Fig. 8, the screws with hollow threaded heads shown in Fig. 9, or the spacing rings with dowel ends, to be headed up on the blades shown in Fig. 10, may be used for 20 connecting the blades, but they will be found more expensive and less desirable for the purpose than the flat clenching pieces. After the connecting pieces have been secured to the blades, each subdivider may be treated with a tinning solution, which will tend to 25 fill all interstices and act as solder, to secure the parts more firmly together.

In order to give greater stability and firmness to the inner ends of the blades of each subdivider, I prefer to secure a narrow flat annulus *m* to the inner ends of the 30 blades, and in the same horizontal plane with the connecting pieces *k*, in the respective subdividers; this annulus also serves as a rigid bearing for each subdivider upon the wings *g* when in proper position within the bowl. The narrow ring *m* and the connecting pieces *k* 35 between the blades give a more open subdivider and freer passage for the liquid which is being acted upon, than that of the prior construction.

An annular perforated flange *z* is provided upon the under side of the disk *D*, similar to that upon the under 40 side of the inner division of the cover in the Patent No.

806,346, to bear upon the uppermost subdivider and hold the interlocked stack of subdividers firmly in position when the machine is in operation.

I claim:

1. In a centrifugal cream-separator, a cover having an 45 annular base and a tubular neck with an annular diaphragm therein, an annular disk of substantially the same diameter as the interior periphery of the bowl, between the cover and liquid subdividers in the bowl, with skim-milk 50 passages between the disk and the cover-base, an annular projection and coincident packing strip respectively upon the adjacent opposed surfaces of the annular diaphragm and the disk, a series of skimmilk passages located without the circumference of the annular projection and extending through the diaphragm into the tubular neck, 55 cream passages through the disk and diaphragm within the circumference of the annular projection and packing strip, and a cream discharge in the tubular neck below the skimmilk discharge opening therein.

2. In a centrifugal cream-separator, a cover having a 60 chambered neck with a diaphragm across its lower end, a disk within the bowl between the liquid subdividers and the cover, a cream chamber between the disk and the diaphragm, closed from the skimmilk passages a cream 65 opening through the disk into such closed chamber, and a cream outlet passage from the closed chamber through the diaphragm.

3. In a centrifugal cream-separator, a cover having a chambered neck with a diaphragm across its lower end, a 70 disk within the bowl between the liquid subdividers and the cover, a cream chamber between the disk and the diaphragm, closed from the skimmilk passages a cream opening through the disk into the closed chamber, and a cream outlet passage from such closed chamber through the diaphragm to a discharge opening in the neck.

4. A subdivider for use in the bowl of a centrifugal cream-separator, consisting of a series of parallel blades, each longitudinally in the form of an involute curve, and securely attached to those immediately adjacent thereto on both sides thereof by separate rigid connecting devices 80 secured at intervals along the length of the blade, substantially in a plane at right angles to the axis of the subdivider.

PERLEY L. KIMBALL.
